UNITED STATES PATENT OFFICE.

JOHN CHARLES WILLIAM STANLEY AND LEONARD BUTLER WRIGHTSON, OF LONDON, ENGLAND.

BOX-CLOSURE.

SPECIFICATION forming part of Letters Patent No. 443,120, dated December 23, 1890.

Application filed December 18, 1889. Serial No. 334,195. (No model.) Patented in England June 20, 1888, No. 9,022; in India March 1, 1889, No. 420, and in Ceylon April 24, 1889, No. 309.

To all whom it may concern:

Be it known that we, JOHN CHARLES WILLIAM STANLEY and LEONARD BUTLER WRIGHTSON, citizens of Great Britain, residing at London, in England, have invented certain new and useful Improvements in Tea Chests, Boxes, or the Like Applicable for Containing other Goods or Articles, (for which Letters Patent have been obtained in Great Britain, dated June 20, 1888, No. 9,022; in India, dated March 1, 1889, No. 420, and in Ceylon, dated April 24, 1889, No. 309,) of which the following is a full, clear, and exact description.

15 Our invention has relation to boxes, chests, and the like designed for containing various articles of merchandise, such as textile fabrics, hardware, chemicals, as well as tea, coffee, spices, and other aromatic substances.

20 The primary object of our invention is to provide such a box or chest, which is of great strength and the edges and corners of which are protected from injury by suitable metallic bands or strips.

25 A further object of the invention is to provide a packing box or chest which is adapted to be readily taken apart and packed for shipment.

With the above objects in view our invention consists in the peculiar construction of the box or chest, as hereinafter fully described, illustrated in the accompanying drawings, and pointed out in the appended claims.

30 In the drawings, Figure 1 is a perspective view of a box or chest constructed in accordance with our invention. Fig. 2 is an enlarged vertical section thereof.

In the construction of our improved box or chest we sheath each of the four sides or walls 40 A with iron along its top and bottom edges, preferably by means of U-shaped hoop-iron strips B, which are riveted or otherwise secured to the said walls in the manner shown in Fig. 1. The sides are united by means of 45 angular hoop-iron corner-pieces C, which may be riveted or otherwise securely fastened to said sides over the corners, and thereby protect the latter from injury. We, however, prefer to so fasten the corner-pieces C that

they may be readily detached from the box 50 to enable the latter to be taken apart to be packed for reshipment, and for this purpose the rivets along one or both sides of each angle-piece C may have washers under their outer rivet-heads, which latter can thus be 55 easily filed off.

The bottom D and lid E of the box are alike in construction, and are respectively provided with hoop-iron strips D' and E', which are riveted or otherwise secured thereto all around 60 on the inner and outer sides. The strips on the outer sides of both bottom and lid project so as to rest upon or against the strips B and are flush with the outer face of the sides. In constructing the bottom and lid we prefer to 65 thicken the same around their edges, as shown at D³ E³, respectively, whereby when the bottom and lid are in place screws or bolts may be used to secure the same to the sides, said screws or bolts entering the thickened portions of the lid and bottom and obviating the liability of splitting or breaking of the same 70 at the points where the screws enter.

The manner of arranging and securing the lid and bottom in place is shown in Fig. 2. 75 When in position, the lid and bottom bear at their outer edges against the strips B upon the inner sides of the walls A, and said bottom and lid are respectively secured to the walls or sides by means of screws D² E², which 80 pass through the strips B and sides and into the thickened portions of the bottom and lid. In order to give the screws a better hold, we first form the screw-threads by means of the screws, and having removed them temporarily 85 we coat the screw-threads so formed with gum or the like, which binds the fibers together and hardens the screw-threads. We may also insert small threaded metallic pieces in the screw-openings in the bottom and lid, which 90 pieces thereby act as nuts for the screws.

Although we have shown a box having both lid and bottom constructed alike and secured in place in the same manner and by similar means, yet it will be understood that the bottom of the box may be secured in any ordinary manner and the lid only be constructed and secured in the manner described.

When the box or chest is to contain tea or similar perishable goods, we line the said box or chest with parchment paper F, or lead paper or other suitable damp-proof inodorous material, having flaps G, backed with calico, if desired. The inner corners of the box may be lined with calico under the paper lining, as shown at H, where the said paper lining is shown broken away.

10 We may place a packing-strip of calico, cloth, or the like between the overlapping sheet-iron edges of the bottom and lid and the lower and upper edges of the sides in order to render the box impervious to moisture.

15 When the boxes are not to be used for tea, we may use india-rubber packing.

The sides, lid, and bottom of the box described we construct of straw-board, wood, or other equivalent material. Either of said materials may be used alone, or it may be covered with very thin perforated or solid sheet-iron; or sheet-iron alone may be used, in which case we use for the lid and bottom a ring of straw-board, wood, or the like all around the edge for making up the depth or thickness required at this place. This ring would be secured between the outer metal sheeting of the bottom and lid, respectively, and the inner hoop-iron rings E' and D', respectively.

25 30 What we claim, and desire to secure by Letters Patent, is—

1. In combination with a box or chest having its edges and corners provided with metallic strips secured thereto, the sides of said

box being provided along their upper edges with metallic strips, a lid for said box provided along its top edges with metallic strips, said lid being adapted to fit within the sides of the box with its metallic strips resting upon the metallic strips of the sides, and screws passing through the latter into the lid, as described.

2. In combination with a box or chest having its edges and corners provided with metallic strips secured thereto, the sides of said box being provided along their upper edges with metallic strips, a lid for said box provided with the thickened portion E³ and with metallic strips along its top edges, said lid being adapted to fit within the sides of the box with its metallic strips resting upon the metallic strips of the sides, and screws passing through the latter into the thickened portion of the lid, as described, for the purpose specified.

JOHN CHARLES WILLIAM STANLEY.
LEONARD BUTLER WRIGHTSON.
